UNITED STATES PATENT OFFICE

163,596

FOOTAGE METER

Simon Gancher, Port Washington, N. Y.

Application August 11, 1949, Serial No. 4,420

Term of patent 7 years

(Cl. D52—1)

To all whom it may concern:

Be it known that Simon Gancher a citizen of the United States of America, residing at Port Washington, in the county of Nassau and State of New York, has invented a new, original, and ornamental Design for a Footage Meter, of which the following is a specification, reference being had to the accompanying drawing, forming a part hereof.

On the drawing,

Fig. 1 is a front perspective view of a footage meter, showing my new design;

Fig. 2 is a rear perspective view of the footage meter.

I claim:

The ornamental design for a footage meter, as shown.

SIMON GANCHER.
